CLAIM

The ornamental design for a storage-preventing base for shopping cart, as shown and described.

DESCRIPTION

FIG. 1 is a side elevational view of a storage-preventing base for shopping cart showing my new design;

FIG. 2 is a top plan view thereof;

FIG. 3 is a front elevational view thereof; and

FIG. 4 is a perspective view thereof it being understood that the broken lines are for illustrative purposes only.
